UNITED STATES PATENT OFFICE

138,433

DESIGN FOR A COMMUNION CUP TRAY

Allan P. Lindblad, Winchester, Mass.

Application June 16, 1944, Serial No. 114,028

Term of patent 14 years

(Cl. D44—10)

To all whom it may concern:

Be it known that I, Allan P. Lindblad, a citizen of the United States, residing at Winchester, in the county of Middlesex and Commonwealth of Massachusetts, have invented a new, original, and ornamental Design for Communion Cup Trays, of which the following is a specification, reference being had to the accompanying drawing, forming a part thereof.

I claim:

The ornamental design for a communion cup tray, substantially as shown and described.

ALLAN P. LINDBLAD,
